UNITED STATES PATENT OFFICE.

THOMAS WATSON, OF BRIDGE OF WEIR, SCOTLAND, ASSIGNOR TO ERNEST SYMINGTON COATS, OF PAISLEY, SCOTLAND.

COP-BUILDING MECHANISM FOR SPINNING AND DOUBLING MACHINERY.

SPECIFICATION forming part of Letters Patent No. 691,991, dated January 28, 1902.

Application filed April 12, 1901. Serial No. 55,514. (No model.)

To all whom it may concern:

Be it known that I, THOMAS WATSON, a subject of the King of Great Britain and Ireland, and a resident of Bridge of Weir, in the county 5 of Renfrew, Scotland, (whose postal address is Glenapp, Bridge of Weir, Scotland,) have invented certain Improved Cop-Building Mechanism for Spinning and Doubling Machinery, (for which application for British patent has been made, No. 16,816, dated September 21, 1900,) of which the following is a specification.

This invention has for its object to provide improved cop-building mechanism for spinning and doubling machinery whereby the yarn is wound on the spindle more closely and firmly than by present existing means.

In the accompanying drawings, Figure 1 is a side elevation, and Fig. 2 is a transverse section, of a spinning-frame provided with the herein-described improvement. Fig. 3 is a side elevation, and Fig. 4 is a front elevation, of change-levers used in the improved mechanism. Figs. 5, 6, and 7 are respectively a front elevation, a plan, and a side elevation, of a stop-frame which acts in conjunction with the change-levers. Fig. 8 is a view showing the wound cop.

As shown in the drawings, fliers 1, having 30 grooved pulleys, are mounted on the stationary rail 4 and surround the spindles 3. These fliers may be of ordinary construction and may be driven by ropes from the drums 13 and 14. For the sake of clearness I have not shown 35 these ropes, which are not essential, the herein-described invention pertaining to the spindle and its operating mechanism.

The spindle is arranged to move up and down during the winding, so as to build the 40 cop, a regular upward-and-downward movement being imparted to the movable rail 29, which works in guides 42, formed on the framing, the stroke of the rail being gradually reduced in order to build the cop with the required 45 site taper at the ends. The mechanism for moving the building-rail 29 is as follows: A vertical shaft 43, Figs. 1 and 2, is mounted on the framing and is driven from the main shaft 44, preferably through spur-and-worm 50 and worm-wheel gearing 45, as shown. The vertical shaft 43 has on its lower end a bevel-pinion 46, which gears at one time with one of a pair of bevel-pinions 47 48, formed on a

piece 49, fitted to slide on a cross-shaft 50, the inner end of the pinion-piece being formed 55 with clutch-jaws 51, which fit corresponding projections 52 on a clutch-piece 53, fixed to the shaft. The pinion-piece 49 may, however, be connected to the shaft in any other convenient way. The cross-shaft 50 has fixed to 60 it a worm 54, gearing with a worm-wheel 55, fixed to a shaft 56, mounted longitudinally on the framing, this shaft having fixed to it a winding drum or barrel 57 (shown in Figs. 1 and 2) for imparting movement to the building-rail 29. The winding-drum 57 is suitably connected, preferably by adjustable chains 58, to similar drums 59 60, fixed to shafts 61 62, mounted longitudinally on the framing on each side of the machine, the connection to the 65 building-rail 29 being finally formed by other drums 63 64, fixed to the side shafts, these drums being also connected by chains 65 66 to studs 67 68, fixed to the rail, the drums 63 imparting the upward movement to the rail and 70 the drums 64 the downward movement. The direction of movement up or down of the building-rail 29 depends upon which of the cross-shaft pinions 47 48 is in gear with the vertical-shaft pinion 46, the cross-shaft pinions being 75 made to gear in turn with the vertical-shaft pinion by the following automatic arrangement: A two-armed lever 69, Figs. 3 and 4, is mounted vertically on a stud 70 on the framing and has its lower end formed with a fork 80 71, which engages with the pinion-piece 49 on the cross-shaft 50. The upper arm 72 of this change-lever 69 has fixed to it a tappet 73, which engages in a slot 74, formed through the arm 75 of a bell-crank lever 76, pivoted 85 on a stud 77 on the framing and acting in front of the change-lever 69, a clearance-opening 78 being formed through this latter lever 69 for the stud to pass through and to permit the lever to travel. The tappet 73 in its normal 90 position bears against one end of the slot 74, as shown in Fig. 4. An extra or auxiliary tappet 79 is provided on the upper arm of the change-lever 69, this tappet engaging in a square-shaped slot 80, formed through the 95 arm of the bell-crank. A shifting bolt or pusher 81 is arranged to move up and down on guides in the change-lever frame-piece 82. The guides consist of studs 83, which are screwed into the frame 82, the heads 84 of the 100 studs projecting through slots 85 in the pusher 105

81, and thereby constituting the guide parts. The lower end 86 of the pusher 81 is V-shaped and acts on a similarly-shaped part 87, formed on the end of the upper arm 75 of the bell-crank 76. The pusher 81 is controlled by a spring 88, the upper end of the spring being attached to the pusher and the lower end to the frame-piece 82. A locking device for the change-lever tappet 73 is provided in connection with the pusher 81, the locking-piece 89 being arranged to move up and down on the outer ends of the pusher-guides 84, these outer ends engaging in slots 90, formed through the locking-piece 89, which is kept on the guides by pin-and-washer attachments 91. The lower end of the locking-piece is formed with a toe 92, which is arranged to fall in front of the upper tappet 73 on the change-lever 69, so as thereby to lock the lever in the proper position. The toe is raised clear of the tappet 73 at the proper time by the pusher 81, a pin 93, fixed to the pusher, acting on the upper end of a slot 94, formed through the locking-piece 89. A stop or catch 95, controlled by a spring 96, is provided to act on the pointed end 97 of the upper arm of the change-lever 69, the pointed end engaging in turn in two suitable indentations 98 99, formed on the under side of the catch 95. The other arm 100 of the bell-crank 76 extends inward, occupying normally a partly-horizontal position and having on its outer end a tappet 101, arranged to be acted on by stops 102 103, which are preferably of a cushion-type. Each stop is fitted to work in an adjustable socket 104, one end of the stop being formed with a head 105, and the other end passing through the socket and provided with a retaining pin or catch 106.

The cushioning device consists of a spring 107, which is arranged within the socket 104, so as to act between a shoulder 108 on the stop and the inner end 109 of the socket. This cushioning arrangement prevents any jarring action when the tappet 101 comes in contact with the stops. The sockets 104 for the stops 102 103 are screwed into nut-pieces 110 111, working, respectively, on the upper and lower portions of a spindle 112, mounted in a frame 113, Figs. 5, 6, and 7, formed with a flange or bracket 114, by means of which it is fixed to the movable or building rail 29, the upper screwed part 115 of the spindle having preferably a right-hand thread and the lower screwed part 116 a left-hand thread, the spindle being fitted in the frame so that it cannot move endwise. At the commencement of the winding the stop-nuts 110 111 are placed at the desired positions on the vertical screwed spindle 112 by means of an adjusting-handle 117, fixed to a ratchet-wheel 118, fixed to the upper end of the spindle. In the drawings the building-rail 29 on one side of the machine only is shown, the rail being shown on its upward stroke and set at about half-stroke. The building-rail on the other side of the machine is similarly set and is on its downward stroke. When the upward-

moving rail 29 reaches to nearly the end of its stroke, the lower cushion-stop 103 acts against the tappet 101, on the bell-crank lever 76, so as thereby to turn the lever and cause the other or inner end of the slot 74 in the vertical arm 75 of the bell-crank to bear against the upper tappet 73 in the change-lever 69. Just immediately before the end of the slot 74 reaches the upper tappet 73 the auxiliary tappet 79 is acted on by the bell-crank, so as to impart a slight starting movement to the change-lever. During this first movement of the bell-crank 76 one side 119 of its V-shaped upper end acts against the corresponding side 120 on the lower end of the pusher 81, so as thereby to raise the pusher against the action of the spring 88. The locking-toe 92 is also raised shortly afterward along with the pusher, so as to clear the upper tappet 73, the vertical arm 75 of the bell-crank traveling far enough around, so as to cause the corresponding opposite V-shaped parts 121 122 on the pusher and bell-crank just to begin to come in contact with each other. The pusher-spring 88 then acts so as to force down the pusher 81 against the vertical arm 75 of the bell-crank. The V-shaped side 121 of the pusher 81 is thus pressed down against the corresponding part 122 of the vertical arm 75 of the bell-crank 76, so that the bell-crank lever is turned still farther around. This second movement of the bell-crank 76 produces a turning movement of the change-lever 69 by reason of the end of the slot 74 in the vertical arm of the bell-crank bearing against the upper tappet of the change-lever. The change-lever 69, which is connected to the cross-shaft pinions 47 48, is thus turned so as to place the inner cross-shaft pinion 48 out of gear and the outer one 47 in gear with the vertical-shaft pinion 46, thereby changing the direction of the movement of the building-rails. When the movements of the bell-crank and change-lever are completed, the locking-toe 92 has fallen in front of the other side of the upper tappet 73 of the change-lever 69, and the pointed end 97 of the lever engages in the other indentation 98 in the spring-stop 95, so that the change-lever is by this means firmly locked in position until another action of the parts takes place. The bell-crank lever 76 is also held in position until another action of the parts by the V-shaped end of the pusher 81 pressing against the end of the vertical arm 75 of the bell-crank. A similar action of the parts takes place during the opposite movements of the building-rails.

The stroke of the building-rails is reduced in the following way: A tappet-lever 123 is arranged to turn loosely on the upper end of the screwed spindle 112 in the stop-frame 113. The tappet-lever 123 has fitted to its upper side a pawl 124, which is pivoted on a pin 125 and engages with the teeth on the ratchet-wheel 118, fixed to the spindle 112, a spring-piece 126 being provided to act on the outer end or boss part 127 of the pawl, so as

to keep it always in contact with the wheel. During each stroke of the building-rails 29 the tappet-lever 123 encounters an inwardly-projecting cam-piece 160, Fig. 2, fixed to the upper fixed rail 4, so that the tappet-lever is thereby turned inward, so as to move the pawl 124 and turn the ratchet-wheel 118 and screwed spindle 112. This movement of the screwed spindle 112 causes the nut-stops 102 5 to approach each other, thus causing them to act sooner on the bell-crank lever 76, and thereby effecting the necessary reduction in the stroke of the building-rails 29. An adjusting-pin 128, working in a bracket 129, is 10 provided for adjusting or reducing the positive turning movement of the tappet-lever 123, so as thereby to adjust or reduce the movement of the nut-stops 102 103 when desired. The tappet-lever 123 when not in action is always in contact with the end of the adjusting-pin 128, being held in this position by the action of a spring 130, having its inner end fixed to the tappet-lever and its outer end to the side of the bracket in which the adjusting-pin works.

I claim as my invention—

1. The combination of the movable part of a reversing-gear of a cop-building mechanism and a frame therefor with a change-lever pivoted to the frame and acting on said movable part, a bell-crank lever pivoted to the frame and acting on said change-lever, the building-rail carrying stops to act on the bell-crank lever, a spring-operated pusher to be 30 first acted on by and then to throw the bell-crank lever and a locking-bolt carried by the pusher to lock the change-lever at the ends of its movements.

2. The combination of the movable part of a reversing-gear of a cop-building mechanism and a frame therefor with a change-lever pivoted to the frame and acting on said movable part, said change-lever having a tappet, a bell-crank lever pivoted to the frame and acting on the tappet and having a V-shaped end, the building-rail carrying stops to act on the bell-crank lever, a spring-operated pusher to be first acted on by and then to throw the bell-crank lever and a locking-bolt carried by the pusher to engage the tappet, as and for the purpose described.

3. The combination of the movable part of a reversing-gear of a cop-building mechanism and a frame therefor with a change-lever pivoted to the frame and acting on said movable part, said change-lever having upper and lower tappets, a bell-crank lever pivoted to the frame and having slots in which said tappets work, the building-rail carrying stops to act on the bell-crank lever, a spring-operated pusher to be first acted on by and then to throw the bell-crank lever and means to lock the change-lever at the ends of its movements.

4. The combination of the movable part of a reversing-gear of a cop-building mechanism and a frame therefor with a change-lever pivoted to the frame and acting on said mov-

able part, a bell-crank lever pivoted to the frame and adapted to act on the change-lever to throw it, said bell-crank lever having a V-shaped end, the building-rail carrying stops to act on the bell-crank lever, a spring-operated V-shaped pusher to coöperate with the V-shaped end of the bell-crank and means to lock the change-lever at the ends of its movements, substantially as described.

5. The combination of the movable part of a reversing-gear of a cop-building mechanism and a frame therefor with a change-lever pivoted to the frame and acting on said movable part, a bell-crank lever pivoted to the frame and acting on the change-lever, the building-rail carrying stops to act on the bell-crank lever, a spring-actuated pusher to be first acted on by, and then to throw the bell-crank lever, and a spring-actuated catch to engage the end of the change-lever, as and for the purpose described.

6. The combination of the movable part of a reversing-gear of a cop-building mechanism and a frame therefor with a change-lever pivoted to the frame and acting on said movable part, a bell-crank lever pivoted to the frame and acting on said change-lever, the building-rail carrying stops to actuate the bell-crank lever, a spring-operated pusher to be first acted on by, and then to throw, the bell-crank lever, means to lock the change-lever at the end of its movements and means for automatically adjusting the stops on the building-rail, as the winding proceeds, all substantially as described.

7. The combination of the movable part of a reversing-gear of a cop-building mechanism and a frame therefor with a change-lever pivoted to the frame and acting on said movable part, a bell-crank lever pivoted to the frame and acting on said change-lever, the building-rail carrying cushion-stops to actuate the bell-crank lever and a spring-operated pusher to be first acted on by, and then to throw the bell-crank lever, all substantially as described.

8. The combination of the building-rail, its actuating mechanism and reversing-gear of a cop-building mechanism and a main frame therefor with a lever controlling the reversing-gear, stops on the building-rail to act on said lever and means for automatically adjusting said stops as the winding proceeds, said means comprising a frame on the rail, guides for the stops, a screw-threaded spindle acting on the stops, a ratchet-wheel on said spindle, a tappet-lever carrying a pawl to act on said ratchet and a cam-piece on the main frame to act on said tappet, substantially as described.

In testimony whereof I have signed my name to this specification in the presence of two subscribing witnesses.
